UNITED STATES PATENT OFFICE.

ANDREW MORRISON, OF PITTSBURG, PENNSYLVANIA.

GUARD-RAIL SYSTEM.

No. 921,140.

Specification of Letters Patent.

Patented May 11, 1908.

Application filed October 14, 1908. Serial No. 457,650.

To all whom it may concern:

Be it known that I, ANDREW MORRISON, of Pittsburgh, Allegheny county, Pennsylvania, have invented a new and useful Guard-Rail System, of which the following is a full, clear, and exact description, reference being had to the accompanying drawings, forming part of this specification, in which:

Figures 1, 2 and 3 are sectional views illustrating different embodiments of my invention. Fig. 4 is a plan view of the tie plate.

My invention has relation to guard rail systems, and is designed to provide a novel construction and arrangement of the main and guard rails, together with the tie or seating plate therefor, whereby the main rail is utilized to hold the guard rail securely fastened against tilting or tipping, and permitting the use of rolled sections for both the main and guard rails without the necessity for special bending operations on the base flanges of such rails.

The nature of my invention will be best understood by reference to the accompanying drawings, which will now be described, it being premised, however, that I do not limit myself to the exact constructions and arrangements of the parts, since these may be varied in detail without departing from the spirit and scope of my invention as defined in the appended claims.

Referring first to the form of my invention shown in Fig. 1, the numeral 2 designates the main rail, 3 the guard rail, and 4 the base or tie plate upon which both rails are seated. In accordance with my invention the main rail 2, which is an ordinary T-rail section, is of less height than the guard rail 3, which is also of an ordinary T-rail section. To support the two rails so that their heads will be at the same height, the tie plate 4 is formed with a raised seating portion 5 at one end, which extends underneath a portion of the base of the main rail, and which is of sufficient thickness to compensate for the difference in the height or depth of the two rails. This base or tie plate may be conveniently formed from a rolled plate having one edge portion folded over upon itself to form the part of increased thickness underneath the main rail, said plate also having the rib or lug 6 against which the outer edge of the base flange of the guard rail 3 is seated. Said plate is also suitably punched to receive the

securing spikes or fastenings for the main rail. The inner base flange 7 of the guard rail extends underneath the base flange of the main rail, so that the guard rail is securely held in place by the main rail, the base flange of the guard rail having one or more spike or openings 8 therethrough to receive the securing spikes for the main rail.

The construction shown in Fig. 2 is similar to that shown in Fig. 1, with the exception that the guard rail is shown as having the major portion of its head at its inner side, and if desired a section may be used for this rail in which the entire head is at the inner side of the rail, rails of this section being well-known in the art. This form has the advantage over that shown in Fig. 1 of permitting the webs of the main and guard rails to be farther apart, while bringing their heads in the same relation to each other. This avoids the necessity for extending the base flange of the guard rail as far underneath the base flange of the main rail as is necessary in the form shown in Fig. 1, thus giving greater opportunity for adjustment of the two rails relatively to each other to compensate for wear on their heads, and also permitting the spike hole 8^a to be placed farther away from the web of the guard rail. The same object may be obtained by the construction shown in Fig. 3, in which the web 9 of the guard rail is inclined inwardly so as to bring its head closer to the head of the main rail.

My invention provides a guard rail system in which rolled sections may be used for both the main and guard rails, and in which the main rail acts to hold the guard rails securely in place without the necessity for special bending operations to enable the base flange of the guard rail to be carried underneath the base flange of the main rail. If desired, the upper surface of the inner flange of the guard rail may be rolled with a flattened portion 10 at its edge to extend underneath the base flange of the main rail, or this flange may be slightly planed off for the same purpose. This is only necessary, however, in case it is desired to get a very close fit, as in other cases the ordinary T-rail section may be employed.

The particular form of base or tie plate herein shown and described may be readily and cheaply manufactured, and specific claim will be made therefor. I do not, how-

ever, limit myself, insofar as the main features of my invention are concerned, to the use of a tie plate of this particular character, since it may obviously be made in other ways.

What I claim is—

1. In a guard rail system, a main rail and a guard rail, the guard rail being of a higher section than the main rail, the base of the main rail being seated in part upon the base of the guard rail and in part upon a separate and independent support; substantially as described.
2. In a guard rail system, a main rail and a guard rail, the guard rail being of a higher section than the main rail and having its base flange extending underneath the base flange of the main rail and held down by the base of the main rail, and a tie or base plate having seating portions of different heights to correspond to the difference in the heights of the two rails; substantially as described.
3. In a guard rail system, a main rail and a guard rail, the guard rail being of a higher section than the main rail, the base of the main rail being seated in part upon the base of the guard rail and in part upon a separate and independent support, the head of the guard rail being eccentric with respect to the

center line of the base of said rail; substantially as described.

4. In a guard rail system, the combination with main and guard rails, of different heights, of a tie or base plate provided with seating portions of different thickness or heights for said rails, the portion of greatest thickness or height being formed by doubling one edge portion of the plate upon itself; substantially as described.

5. In a guard rail system, having main and guard rails of different heights, a rolled tie plate having an edge portion bent upon itself to form an elevated seat for the main rail; substantially as described.

6. In a guard rail system, a main rail and a guard rail, the guard rail being of a higher section than the main rail, the base of the main rail having a holding-down engagement with the base of the guard rail, and means for permitting a lateral adjustment of one rail relatively to the other; substantially as described.

In testimony whereof, I have hereunto set my hand.

ANDREW MORRISON.
